UNITED STATES PATENT OFFICE.

ARTHUR BATES AND GERALD PEGG, OF LEICESTER, ENGLAND, ASSIGNORS TO UNITED SHOE MACHINERY CORPORATION, OF PATERSON, NEW JERSEY, A CORPORATION OF NEW JERSEY.

MACHINE FOR MAKING CLOG-SHOES.

1,326,168.

Specification of Letters Patent. Patented Dec. 30, 1919.

Application filed April 6, 1918. Serial No. 227,114.

To all whom it may concern:

Be it known that we, ARTHUR BATES and GERALD PEGG, subjects of the King of England, residing at Leicester, Leicestershire, England, have invented certain Improvements in Machines for Making Clog-Shoes, of which the following description, in connection with the accompanying drawings, is a specification, like reference characters on the drawings indicating like parts in the several figures.

This invention has reference to machines for use in the manufacture of shoes and is more particularly designed for employment in the manufacture of shoes of a type generally called "clogs" which comprise wooden soles and flexible uppers.

The invention will be described, by way of example, with reference to a particular operation in the manufacture of so-called Lancashire clogs, *i. e.*, clogs in which the margin of the upper which lies in a groove formed in the side of the sole is concealed by a rand strip or welt running around the side of the sole and secured to the sole by fastenings which are driven through the rand strip and the margin of the upper into the sole along the line of the groove. It is recognized, however, that the invention as a whole or certain features thereof may be used in other ways or in other relations such, for example, as in the attachment of uppers to soles in the manufacture of clog shoes without the application of a rand strip. It is therefore intended that the scope of the invention shall be limited only by the language of the appended claims.

An important feature of the invention resides in the provision in a machine for inserting fastenings for securing the margin of an upper in the groove of an outsole of improved work guiding means constructed and arranged for engagement in the groove of the outsole and operating to guide the outsole as it is fed relatively to the fastening inserting mechanism in the attachment of the upper thereto.

According to a further feature of the invention, the arrangement of parts is such that the work is guided with the tread of the sole toward the operator and the line of the groove at the point of operation in full view of the operator. In the illustrated embodiment of the invention, this is effectuated by

the provision of work guiding means having 55 a work guiding surface positioned adjacent to the vertical plane of the forward end of the work abutment and forwardly of the plane of operation of the fastening inserting mechanism.

The invention in one of its aspects resides in the provision of means for guiding a rand strip for application of the strip over the margin of an upper in the groove of an outsole and guiding means constructed and arranged to engage in the groove of the outsole to position the outsole relatively to the rand guiding means so that the rand strip will be properly located in the groove of the outsole. In another aspect, the invention 70 comprises the association with rand guiding means for guiding the rand to position for attachment in the groove of an outsole of means for laying the margin of the upper in proper position in the groove prior to the attachment of the rand and upper to the outsole. In the illustrated construction, the work guiding means which is in the form of a blade is positioned between the operator in working position and the channel of the 80 rand guiding means.

The invention also comprises in a fastening inserting machine provided with a work guide having a blade or the like, the combination with a rand guide of a work penetrating and feeding element such as an awl operating, as shown, through a slot in said rand guide so as to permit work feeding movement of said element.

Still a further feature of the invention 90 consists in the combination with fastening inserting mechanism of a rand guide through which a portion of the fastening inserting mechanism operates, a supplementary rand guide operating to deliver the 95 rand to the first named guide, and a work guiding member in the form of a blade or the like carried by one of said guides.

These and other features of the invention will now be described, with the aid of 100 the accompanying drawings, in connection with a construction illustrating the invention.

In the drawings:—

Figure 1 is a front elevation of a portion 105 of a fastening inserting machine, having applied thereto a construction of work-guiding devices according to the present invention;

Fig. 2 is a side elevation of the rand guide and blade shown in Fig. 1;

Fig. 3 is an inverted plan of part of the devices shown in Fig. 2;

5 Fig. 4 is a side elevation showing the parts of a clog in section and illustrating the positions which the parts of the clog and the rand-guiding and work-guiding devices occupy during the rand-attaching operation;

10 Fig. 5 is a perspective view of part of a clog after the rand-attaching operation has been performed upon the clog;

Fig. 6 is a front elevation of a portion of a fastening inserting machine illustrating 15 a modified form of the invention;

Fig. 7 is an enlarged broken view of the supplementary rand guiding means with the work guiding means mounted thereon, and

20 Fig. 8 is an enlarged view in detail of a portion of the rand guiding means carried by the swinging head of the fastening inserting machine.

The invention is herein illustrated as applied to a fastening inserting machine of the type described in the patent to Louis Goddu, No. 490,624, dated January 24, 1893, and reference may be made to the said Letters Patent for a more complete disclosure of parts not fully described herein. The 25 machine comprises a frame 1 (see Fig. 2) on which is mounted a swinging head which carries a driver guiding and awl guiding member 2 formed with passages to receive the awl 4 and the driver (not shown). The 30 fastenings are supplied to the fastening inserting mechanism by the raceway 6 which serves to guide the fastenings into the driver passage in the member 2. The member 2 is cut away at its lower side adjacent to the 35 driver passage to receive fingers 8 which are normally pressed inwardly from opposite sides of the driver passage by a spring 10. The fingers 8 serve to hold the fastenings in upright position in the driver passage and to prevent lateral deflection of the fastenings as they are driven. The parts 40 thus far described constitute in themselves no part of the present invention for which reason a further description of such elements 45 is deemed unnecessary.

50 Work guiding means is provided of a form to engage in the groove of an outsole to which the margin of an upper is to be attached by the fastening inserting mechanism. Said means comprises a blade 12 elongated in the direction of the feed of the work and carried by an arm 14 slidably mounted on a rod 16 secured in the frame 1 of the machine, the arm 14 being adjustably 55 secured to the frame 1 by a screw 18 the shank of which passes through a slot 20 in the member 14. The slot 20 is elongated transversely of the arm 14 so as to permit 60 adjustment of the member 14 in a direction

parallel to the plane of operation of the 65 fastening inserting mechanism.

The blade 12 has a work guiding surface 22 positioned in advance of the plane of operation of the fastening inserting mechanism and faced away from said plane, or in 70 other words, toward the operator. Said blade engages the shoulder 24 of the groove 26 formed in the outsole 28 and serves thereby to position the outsole 28 relatively to the plane of operation of the fastening inserting mechanism as said outsole is fed relatively to the fastening inserting mechanism in the operation of attaching the margin 75 of the upper 30 in the groove 26 of the outsole. By reference to Fig. 4, it will be seen that the blade 12 is adapted to lie between the shoulder 24 of the groove 26 and the marginal edge 32 of the upper 30 and that the surface 34 of the blade 12 by its engagement with the edge of the upper thrusts 80 back any portion of the upper which may extend past the shoulder of the groove and lays the margin of the upper in proper position in the groove. Moreover, the blade 12 and the adjacent portion of the lower 85 surface 36 of the member 38 which carries the blade 12 serve to press the margin of the upper 30 into the groove 26 and to maintain the margin of the upper in the groove.

Referring particularly to Figs. 2 and 3, 90 the member 38 which carries the work guiding blade 12 is seen to comprise the portions 39 and 41 arranged substantially at right angles to each other, the portion 39 underlying the forward extension 40 of the arm 100 12 and having the blade 12 depending therefrom. The upstanding portion 41 of the member 38 is slotted at 46 and the member 38 is secured to the arm 14 for adjustment relatively thereto transversely of the plane 105 of operation of the fastening inserting mechanism by a bolt or the like 44 passing through the slot 46 into said arm. In the illustrated construction, the portion 39 of the member 38 and the forward extension 110 40 of the arm 14 together constitute a work abutment for determining the vertical position of the work and steadyng it for operation by the fastening inserting mechanism. The work guiding face 22 of the blade 12 115 which, as already stated, is positioned forwardly of the plane of operation of the fastening inserting mechanism, is located adjacent to the forward end of the work abutment 39, 40. The work abutment may, 120 however, be formed separately from the work guiding means in which case the work guiding surface 22 will still preferably be positioned adjacent to the vertical plane of the forward end of said abutment so that 125 the line of the groove in the sole at the point of operation will be visible to the operator.

The invention contemplates the provision of means for guiding a rand strip in the attachment of the strip over the margin of the upper where it lies in the groove 5 of the outsole. Preferably, and as shown, the said means is constituted by the forward extension 40 of the arm 14 which is channeled at 42 to receive the strip. It follows, therefore, that the blade 12 which underlies 10 the channeled extension 40 operates to position the outsole relatively to the rand guiding means. The rand guiding channel 42 of the rand guide 40 is located beneath that part of the member 2 in which the awl 15 4 reciprocates, the floor of the channel 42 being slotted at 43 to permit the awl 4 to pass through the guide into the work and to perform its lateral or work feeding stroke. The work guiding blade 12 is positioned 20 subjacent to the channel 42 of the rand guide, the portion 39 of the member 38 which carries the blade 12 being further provided with a slot 45 alining with the slot 43 of the rand guide. The blade 12 is located 25 in the vertical plane transverse to the direction of feed of the work and passing through the point of engagement of the awl 4 with the work. Obviously, since, in the illustrated construction, the rand guide is 30 formed as a part of the arm 14, the bolt and slot connection 44, 46 constitutes means for adjusting the blade 12 relatively to the rand guide. The operation of the invention will be described, by way of example, by reference 35 to the making of Lancashire clogs.

In the practice of the invention the upper is preferably preliminarily attached to the sole edge and its margin is trimmed. When the clog is presented to the machine, the 40 blade 12 enters between the marginal edge 32 of the margin of the upper 30 (see Fig. 4) and the shoulder 24 of the groove 26 of the sole 28 which shoulder, as the clog sole is being held more or less vertically, is more 45 or less vertical. Although with the shallow groove 26, almost entirely filled by the thickness of upper, which is usual in clogs of this type, there is no definite crease or groove, the operator may, by the agency of this 50 blade, guide the work truly according to the contour of the shoulder and insure the neat disposition of the rand 48 along the margin of the upper as it is being attached to the clog by the nails 50 driven by the machine. 55 The rand guide 40, through which the awl 4 passes insures the perforation of the rand or strip 48 by the awl accurately in the desired position even with the flimsier of the materials used for such strips. The work is 60 also positioned by the upthrust of the same by the operator against the under surface 36 of the work guide 38 which may be roughened to insure more positive engagement with the upper. The blade 12 is preferably 65 located in a plane passing through the edge

of the channel 42 which is the nearer to the operator who consequently presents the work to the machine with the bottom toward him. In this position the operator's view of the part being operated on is not obstructed by 70 the strip 48 itself or by the strip guide 40, which terminates close to the channel 42 and thus extends but a short distance beyond the guiding face 22 of the blade 12, and he is able to adopt an easy position while nevertheless having the material part of the work completely under inspection. The blade 12 may, however, if the strip is to overlap the junction of the upper and sole, be adjustably positioned so that its plane passes 80 through the strip channel 42, the blade being always preferably positioned forwardly of the median line of the channel.

To facilitate the handling of the work with its sole toward the operator the machine head may be carried somewhat more forwardly of its column than usual and to bring the work closer to the operator's eye, the head is also preferably somewhat raised. Since, however, the present invention is not 90 conceived with such parts of the fastening inserting machine, it has not been deemed necessary to describe or illustrate them herein.

As shown in Fig. 1, the machine is provided with a supplementary rand guide 54 supported on a part 56 secured to the machine frame for delivering the rand strip 48 to the guide 40. This guide 54, arranged as shown, performs also the function of a 100 guide foot or rest of the type of the abutment 46 of the machine described in the specification of application Serial No. 174,742, filed June 14, 1917, by Arthur Bates.

Although the guides 40 and 54 are described above as mounted on the machine frame and consequently as stationary, the guide through which the awl penetrates may, if desired, be mounted on the swinging head of the machine as indicated at 40' in Fig. 6 of the drawing, in which case the work guiding blade will preferably be mounted on the stationary guide as indicated at 12' in Figs. 6 and 7 of the drawing. The guide 40' is preferably formed as shown in 110 Fig. 6 and may be secured to the driver guide and awl guiding member 2' by the screw 58 or other suitable means. The guide 40' is formed with a slot 60 through which the awl operates.

The supplementary rand guide 54' is mounted for sliding adjustment in a cradle member 62 and is secured in adjusted position in the cradle 62 by any suitable means (not shown). The cradle 62 is in turn 125 secured to the frame member 56 by a rod 64.

Having fully described the invention, what we claim as new and desire to secure by Letters Patent of the United States is:

1. In a machine of the class described, the 130

- combination with fastening inserting mechanism for securing the margin of an upper in the groove of an outsole of means for feeding the work past the fastening inserting mechanism, and work guiding means positioned substantially in the vertical plane of the point of engagement of the feeding means with the work transverse to the direction of feed of the work and adapted to 5 be received in the groove of the outsole for guiding the outsole as it is held against said work guiding means and fed relatively to said fastening inserting mechanism in the attachment of the upper thereto.
- 10 2. In a machine of the class described, in combination, a frame, fastening inserting mechanism carried by said frame for securing the margin of an upper in the groove of an outsole and work guiding means mounted on said frame independently of the fastening inserting mechanism and formed to present a substantially plane surface for engagement with the shoulder of the groove formed in the outsole.
- 15 3. In a machine of the class described, the combination with fastening inserting mechanism for securing the margin of an upper in the groove of an outsole of work guiding means constructed and arranged for 20 engagement between the edge of the upper and the shoulder of the groove to position the margin of the upper properly in said groove.
4. In a machine of the class described, 25 the combination with fastening inserting mechanism for securing the margin of an upper in the groove of an outsole of work guiding means having a surface adapted to engage the margin of the upper to press it 30 into the groove of the outsole and a second surface disposed below the first-mentioned surface and at an angle thereto and forwardly of the plane of operation of the fastening inserting mechanism and faced 35 away from said plane.
5. In a machine of the class described, 40 the combination with fastening inserting mechanism of a work abutment extending forwardly of the plane of operation of the fastening inserting mechanism and work 45 guiding means having a work guiding surface disposed below the abutment and adjacent to the vertical plane of the forward end of said abutment and constructed and 50 arranged to guide the work by engagement therewith at a point in advance of the plane of operation of said fastening inserting mechanism so that the part of the work by which the work is guided is visible to 55 the operator.
6. In a machine of the class described, 60 the combination with fastening inserting mechanism of a member formed to present a surface against which the work may be 65 maintained to locate it in operative rela-
- tion to the fastening inserting mechanism, and a blade extended downwardly from said member and constructed and arranged for engagement in a groove formed in the work.
7. In a machine of the class described, 70 the combination with fastening inserting mechanism for securing the margin of an upper in the groove of an outsole of work guiding means comprising a blade constructed and arranged for engagement in the 75 groove of the outsole between the shoulder of said groove and the marginal edge of the upper.
8. In a machine of the class described, 80 the combination with fastening inserting mechanism of a member mounted adjacent to the fastening inserting mechanism and provided with a downwardly extending blade elongated in the direction of the feed of the work, and a work abutment adjacent to said member disposed in substantial alinement with said blade.
9. In a machine of the class described, 85 in combination, a frame, fastening inserting mechanism carried by said frame, a member mounted on said frame for adjustment in a direction substantially parallel to the plane of operation of the fastening inserting mechanism and formed to present a surface against which the work may 90 be maintained to locate it in operative relation to the fastening inserting mechanism, and a blade extending downwardly from said member and elongated in the direction of feed of the work.
10. In a machine of the class described, 95 a frame, fastening inserting mechanism mounted for swinging movement relatively to said frame, and a member fixed to the frame and having a part lying adjacent to the plane of operation of said fastening inserting mechanism on the work, said part having a blade extending laterally therefrom and formed with a narrow edge extending in a direction substantially parallel 100 to the plane of operation of the fastening inserting mechanism.
11. In a machine of the class described, 105 the combination with fastening inserting mechanism for securing a rand and the margin of an upper in the groove of an outsole of means for guiding the rand and work guiding means constructed and arranged to engage in the groove of the outsole and operating to position the outsole relatively to 110 the rand guiding means.
12. In a machine of the class described, 115 the combination with fastening inserting mechanism for securing a rand and the margin of an upper in the groove of an outsole of means for guiding the rand and means for laying the margin of the upper in proper position in the groove prior to the attachment of the rand and upper to the outsole.
13. In a machine of the class described, 120

the combination with fastening inserting mechanism for securing a rand and the margin of an upper in the groove of an outsole of means for guiding the rand and work 5 guiding means subjacent to said rand guiding means constructed to engage in the groove of the outsole.

14. In a machine of the class described, the combination with fastening inserting 10 mechanism for securing a rand and the margin of an upper in the groove of an outsole of means for guiding the rand and work guiding means constructed and arranged to guide the outsole upon movement of the out- 15 sole relatively to said fastening inserting mechanism in a path such that the rand will be laid in the groove of the outsole.

15. In a machine of the class described, the combination with fastening inserting 20 mechanism for attaching a rand and the margin of an upper in the groove of an outsole, of means for guiding the rand comprising a channeled portion, and work guiding means having a work guiding surface positioned 25 forwardly of the median line of the channel of said rand guiding means.

16. In a machine of the class described, the combination with fastening inserting mechanism for securing a rand and the 30 margin of an upper in the groove of an outsole of means for guiding the rand having a channeled portion and work guiding means having a guiding surface positioned to one side of the channeled portion of said rand 35 guiding means and faced away from the channeled portion of the rand guiding means.

17. In a machine of the class described, the combination with fastening inserting 40 mechanism for securing a rand and the margin of an upper in the groove of an outsole of means for guiding the rand having a channeled portion, work guiding means having a guiding surface positioned in advance 45 of the channeled portion of said rand guiding means and facing away from the channeled portion of the rand guiding means, and means for adjusting said work guiding means relatively to said rand guiding means.

50 18. In a machine of the class described, the combination with fastening inserting mechanism for securing a rand and the margin of an upper in the groove of an outsole of means for guiding the rand having a 55 channeled portion and work guiding means mounted on said rand guiding means having a guiding surface positioned in advance of the channeled portion of said rand guid-

ing means and facing away from the channeled portion of the rand guiding means. 60

19. In a machine of the class described, the combination with fastening inserting mechanism, of rand guiding means provided with a slot for operation therein of said fastening inserting mechanism, supplementary 65 rand guiding means arranged to guide the rand to said first-mentioned rand guiding means and constructed to constitute an abutment for the work, and a work guiding member carried by one of said rand guiding 70 means.

20. In a machine of the class described, the combination with fastening inserting mechanism for securing a rand and the margin of an upper in the groove of an outsole, 75 of a rand guide operable to lay the rand in the groove of the outsole, a supplementary rand guide for delivering the rand to the first-named guide, and a blade carried by one of said guides and constructed and arranged for engagement in the groove of the outsole to position the work relatively to the rand guide.

21. In a machine of the class described, the combination with fastening inserting 80 mechanism, of rand guiding means provided with a slot for operation therein of said fastening inserting mechanism and work guiding means carried by said rand guiding means and having a work guiding face arranged in advance of the plane of operation 85 of said fastening inserting mechanism.

22. In a machine of the class described, the combination with fastening inserting mechanism of means for guiding a rand, and 90 work guiding means mounted adjacent to the rand guiding means, said rand guiding means and said work guiding means being provided with aligned slots for operation 95 therein of said fastening inserting mechanism.

23. In a machine of the class described, the combination with fastening inserting mechanism for securing a rand and the margin of an upper in the groove of an outsole, 100 of a rand guide provided with a slot, a work feeding member operable in said slot, and a work guide associated with said rand guide having a blade constructed and arranged for engagement in the groove of the outsole to 110 position the work relatively to the rand guide.

In testimony whereof we have signed our names to this specification.

ARTHUR BATES.
GERALD PEGG.
